METERING PUMP

Kenneth W. Crossman, Willow Grove, Pa., assignor to The Edwin H. Fitler Co., Philadelphia, Pa., a corporation of Pennsylvania

Application August 26, 1943, Serial No. 500,158

4 Claims. (CL. 103—171)

This invention relates to metering pumps for displacing and at the same time metering fluids en route from a source of supply to a point of delivery where the fluid is to be utilized.

Amongst the objects of my invention are to generally simplify the construction of pumps of the kind referred to with a view toward reducing the number of the parts, and so insure against easy derangement in service, and to obviate the necessity for frequent attention in service.

A further aim of my invention is to secure the above advantages in a pump which is immune against leakage during idle or quiescent periods, and which can therefore be relied upon for accurate metering.

Although applicable to other uses, pumps constructed in accordance with my invention are particularly adapted for employment with cordage or rope-making machines where it is desirable to apply to the fibers which enter into the formation of such products, oil or other preservative solutions in definite uniform quantities, and where leakage during the idle or quiescent periods of the pumps would result in excessive soaking of the fibers and consequent irregularities in the appearance and quality of such products.

One way in which the foregoing and other objects and important advantages can be realized in practice will appear from the following detailed description of the attached drawings.

Fig. 1 is a perspective view of a metering pump conveniently embodying my invention.

Fig. 2 shows the pump in horizontal section.

Fig. 3 is a section taken as indicated by the angled arrows III—III in Fig. 2.

Figs. 4—6 are fragmentary sectional views taken as indicated respectively by the angled arrows IV—IV, V—V and VI—VI in Fig. 3.

Fig. 7 is a perspective view of the drive shaft of the pump with the incorporated flow control valve means; and

Fig. 8 is a perspective view of the piston element of the pump.

As herein illustrated, my improved metering pump has a housing 1 which affords a pair of axially-aligned horizontally-arranged cylinders 2 and 2a in which operate the opposite ends of a piston element 3 with a central recession or cutout at 4. Also as shown, the housing 1 provides a tubular bearing extension 5 at right-angles to the axis of the cylinders 2 and 2a for the journaling of a drive shaft 6. To the inner end of the drive shaft 6 is secured a rotary eccentric actuator 7 which revolves in an opening in a follower block 8 slidably engaged, with capacity for

up and down movement, within the central cut or recess 4 of the piston element 3. At 9 the drive shaft 6 is diametrically enlarged for the purposes of a control valve with crosswise notches or cuts at opposite sides, the notches 10 and 11 constituting a pair and being transversely aligned, while the individual notches 12 and 13 are spaced from each other and from said notches 10 and 11 longitudinally of the shaft. From Fig. 2 it will be noted that the notches 10 and 11 are adapted to register with passages 14 and 15 in the pump casing, said passages in turn communicating with crosswise branches 16 and 17 formed in cover plates 19 and 20 that close the outer ends of the cylinders 2. The ports 12 and 13, on the other hand, are adapted to register respectively with correspondingly spaced internal annular grooves 21 and 22 formed in the bore of bearing 5 and communicating with inlet and outlet ports 23 and 24 which are threaded for connection of piping 25 and 26. As shown, longitudinal ducts 27 and 28 in the enlarged portion 9 of the shaft 6 respectively connect the recesses 10 and 12 with the recesses 11 and 13. A detachable cap piece 29 removably secured to the end of the bearing 5 with interposition of a packing gasket at 30 serves to hold the shaft 6 in place in the assembly, with its diametrically reduced end 6a protruding and carrying a power application means 31. For convenience of attachment of the pump to the machine or apparatus with which it is to be employed, the casing 1 is formed with a base 32 having apertures 33 for passage of anchoring bolts or the like; and for convenience of access to the eccentric 7, the casing is further provided with a removable cover plate 34.

The operation of the pump is as follows: Let it be assumed that the shaft 6 is being rotated in the direction indicated by the arrow in Fig. 2 and that the piston element 3 is moving in the direction shown by the arrow thereon in that figure. As a consequence the fluid being pumped is drawn in through the inlet 25, and passes by way of the groove 21 and the recess 12 in the enlargement 9 of the shaft 6, the ducts 27, port 10, and passages 14 and 16 into the cylinder 2. At the same time oil previously taken into the other cylinder 2a is being displaced by way of the passages 17 and 18, recess 11 in the enlargement 9 of the shaft 6, duct 28, recess 13 and groove 22 for discharge by way of the outlet port 24 into the pipe 26.

My improved pump is simple by virtue of having but two moving parts, to wit, the one-piece piston element 3 and the shaft 6 with the incorporated valve 9. The pump moreover is unique in

that it can be easily and quickly disassembled in the event that replacements should become necessary after protracted periods of service, simply by removing one of the end covers 19 or 20, the top plate 34 and the cap piece 29. With this accomplished the shaft 6 can be drawn forwardly out of the bearing 5, the follower 8 withdrawn from above, and the piston element 3 withdrawn through the cylinder corresponding to the removed cover 19 or 20 as the case may be, and these parts as quickly reassembled or replaced by others if found to be defective for any reason. Immunity to leakage during idle or quiescent periods is insured through elimination of separate spring-biased ball or poppet suction and pressure-responsive valves such as are ordinarily used in pumps and which are liable to stick or to become otherwise easily deranged.

Having thus described my invention, I claim:

1. In a metering pump, a casing affording a pair of opposingly arranged cylinders, said casing having a valve bore, at right angles to the cylinders, fluid flow passages leading from the remote ends of the cylinders and terminating respectively in aligned relation at opposite sides of the bore, and fluid inlet and outlet passages extending laterally from opposite sides of the bore in spaced relation to each other and to the terminals of the flow passages; a piston element common to the two cylinders, means for actuating the piston element; and a valve member in the bore rotated in synchronism with the reciprocations of the piston, said valve member having a pair of transversely-aligned lateral recesses, adapted to alternately register respectively with the terminals of the flow passages, in the casing, individual lateral recesses in its opposite sides to intermittently register respectively with the inlet and outlet ports, and longitudinal ducts respectively connecting the two laterally aligned recesses with the spaced individual recesses.

5 2. In a metering pump, a casing affording a pair of opposingly-arranged cylinders, a bearing extending at right angles to the axis of the cylinders, fluid flow passages leading from the remote ends of the cylinders and terminating respectively 10 in aligned relation at opposite sides of the bore in the bearing, and fluid inlet and outlet ports extending laterally from opposite sides of the bore in spaced relation to each other and to the terminals of the flow passages; and a drive shaft journaled in the bearing and having actuating means at its inner end for operating the piston, a valve portion with a pair of transversely-aligned lateral recesses which during rotation of the shaft alternately register respectively with the terminals 15 of the flow passages in the casing, individual lateral recesses in its opposite sides to intermittently register respectively with the inlet and outlet ports aforesaid, and ducts longitudinally of the shaft respectively between the two laterally-aligned recesses and the spaced individual recesses of said valve portion.

20 3. A metering pump according to claim 2, wherein the casing has removable covers which close the remote ends of the two cylinders, and 25 which respectively provide portions of the two fluid flow passages within the casing.

4. A metering pump according to claim 2, wherein the outer end of the bearing is closed by a shaft retaining cap; and wherein the shaft 30 has a diametrically reduced end portion protruding through the cap for power application.

KENNETH W. CROSSMAN.
